US00D698943S

(12) **United States Design Patent**
Johnston

(10) **Patent No.:** **US D698,943 S**
(45) **Date of Patent:** **** Feb. 4, 2014**

(54) **WALL BASE**

(75) Inventor: **Curt Johnston**, Auburn, OH (US)

(73) Assignee: **Johnsonite Inc.**, Chagrin Falls, OH (US)

(**) Term: **14 Years**

(21) Appl. No.: **29/417,889**

(22) Filed: **Apr. 10, 2012**

(51) **LOC (10) Cl.** **25-01**

(52) **U.S. Cl.**

USPC **D25/119**

(58) **Field of Classification Search**

USPC 52/290, 287.1, 220.7, 211, 242, 204.53;
D25/138, 119, 136

(57) **CLAIM**

The ornamental design for a wall base, as shown and described.

DESCRIPTION

FIG. 1 is a perspective view of the wall base according to the invention;

FIG. 2 is a top view of the wall base as shown in FIG. 1;
FIG. 3 is a front view of the wall base as shown in FIG. 1;
FIG. 4 is a side view of the wall base as shown in FIG. 1;
FIG. 5 is a rear view of the wall base as shown in FIG. 1;
FIG. 6 is a side view of the wall base as shown in FIG. 1,
shown from the opposite side of that shown in FIG. 4; and,
FIG. 7 is a bottom view of the wall base as shown in FIG. 1.
The broken away ends indicate that the wall base has no
specific length.
